UNITED STATES PATENT OFFICE.

HENRY E. THOMPSON, OF NEWARK, NEW JERSEY.

CLOSURE FASTENER.

Application filed January 29, 1925. Serial No. 5,577.

This invention relates to closure fasteners and has for its object to provide a construction more simple in construction and more efficient in use than those heretofore proposed:

With these and other objects in view the invention consists in the novel details of construction and combinations of parts as will be more fully hereinafter disclosed and particularly pointed out in the claims.

Referring to the drawings forming a part of this specification and in which like numerals designate like parts in all the views;

Figure 1 is a vertical sectional view showing the invention as applied to a window and a screen therefor;

Figure 2 is a view similar to Figure 1 but showing the screen in locked position;

Figure 3 is a detail view from the outside of the window showing one of the supports for the screen;

Figure 4 is a horizontal sectional view taken on the line 4—4 of Figure 2 and looking in the direction of the arrows;

Figure 5 is a detail view partly in section and partly in elevation of the latching mechanism;

Figure 6 is a view in elevation illustrating the parts shown in Figure 2 when viewed from the inside of the window;

Figure 7 is a fragmentary detail view of the invention showing the arrangement of parts just before the closing of the screen;

Figure 8 is a fragmentary detail view illustrating the parts shown in Figure 7 after the screen has been latched in closed position against the window casing;

Figure 9 is a fragmentary sectional view taken on the line 9—9 of Figure 2 and looking in the direction of the arrows;

Figure 10 is a detail perspective view of the latching foot of the spacing bar;

Figure 11 is a sectional view of a modified application of the invention to a roof man-hole; and

Figure 12 is a detail view partly in section of a modified form of the bracket member of the invention.

In the drawings 1 represents the window frame and 2 the casing thereto, while 3 represents the window opening in said frame. 4 is the bottom member of the window frame, 5 represents a side member thereof while 6 is the window sill.

55 A frame, generally indicated by the nu-

meral 10, is provided with any suitable screen material 11 secured to said frame 10 as by the moulding strips 12. The upper and outer edge 13 of the top member 14 of the frame 10 is beveled as indicated to correspond with and abut the inclined surface 15 of the casing 2. In a similar way the bottom strip 16 of the frame 10 is provided with the inclined surface 17 to correspond with and substantially fit against the inclined surface 18 of the window sill 6 when said frame 10 is in closed position relative to the window casing. The entire frame 10 is adapted to swing on the hooks 20 secured to the upper casing 2, said hooks being engaged by the slotted members 21 secured to the upper member 14 of the frame 10, in the usual and well known manner. Secured to one of the side members, such as 25, of the frame 10 is the angle member 26 provided with the pin 27 pivotally supporting a spacing bar 30.

The spacing bar 30, see Figures 1, 7, 8 and 11, has a cam notch 31 in one edge thereof near the pivot 27, a plurality of holes 32 disposed in spaced relation to each other, and a holding notch 33 located in the same edge with the cam notch 31 but disposed beyond the holes 32 and near the free end of the bar 30. The extreme free end of the bar 30 is bent substantially at right angles to the main body portion thereof to form a foot 35 the side edges of which are inclined relatively to said body portion as clearly shown in Figures 4, 5, 6 and 10. This foot 35 is provided with a suitable opening 36 to receive the bolt of the latch 40 secured to said frame 10 near the bottom member 15 thereof. Also one edge of the foot 35 is beveled as at 37 to aid the bolt of said latch 40 in engaging the aperture 36 of the spacing bar, all as will be clear from the drawings.

The latch 40 may be of any suitable type such as that indicated in the drawings where in the bolt 41 thereof is controlled as by the spring 42 and operated by the thumb knob 43 secured to the said bolt and working through a slot 44 in the casing of the latch 40. Said latch is so disposed on the frame 10 of the screen that the spacing bar 30 when swung from its pin 27 downwardly will cause the opening 36 in the foot 35 of said bar to be engaged by the bolt 41 of said latch as clearly shown in Figures 1, 2 and 6.

Secured to the side 5 of the frame 1 of the

window is the bracket 50, see Figures 1, 6, 7, 8 and 9. This bracket 50 comprises the bridge portion 51 provided with a thumb screw 52 threaded therethrough and having a shank sufficiently long to engage one of the holes 32 of the spacing bar 30 to hold the latter against movement. The bracket 50 is secured to the frame member 5 at one end by a screw 53 disposed through the apertured ear 54 of the said bracket, said ear 54 contacting with the frame member 5 and spaced from the bridge 51 as by the connecting portion 55 of said bracket. The other end of the bracket 50 is formed a little differently, see especially Figure 9, being provided with an apertured ear 56 secured to the bridge 51 by the connecting portion 57 which is of less length than the other connecting portion 55, so that said ear 56 is parallel to but spaced from the frame member 5 in order that the securing bar 30 may be passed between said ear 56 and the frame member 5 when desired. A screw 60 passed through the apertured ear 56 into the frame member 5 will secure said spacing bar 30 within the bracket member 50 as will be readily seen from the drawings.

The operation of the device is as follows: When the opening, such as the window in the drawings, is desired to be closed by the screen 11, the frame 10 holding this screen is swung on the hooks 20 secured to the casing 2. The screw 60 of the bracket member 50 secured to the frame 1 is then removed and the spacing bar 30 inserted within the bracket 50 by passing the bar between the ear 56 of the bracket and the side member 5 of the frame, whereupon the screw 60 is then replaced to prevent the spacing bar 30 from leaving the said bracket. The frame 10 is then allowed to swing in toward the window frame 1 and the bar 30 turned about the pivot 27 in a downward direction and the foot 35 moved toward the bottom member 16 of the frame 10 so as to have the aperture 36 of the said foot engaged in locked position by the bolt 41 of the latch 40. During this operation the inclined edge 13 at the top of the frame 10 will abut the inclined edge 15 of the casing and likewise the inclined edge 17 at the bottom of the frame 10 will substantially fit the inclined surface 18 of the sill 6. The hooks 20 and the socket members 21 engaged thereby are so disposed that the frame 10 will tightly fit the casing 2 as well as the frame 1. Also the spacing bar 30, the angle member 26, the bracket member 50, and the latch 40 are all so disposed relative to each other that when the screen is in closed position as shown in Figure 2, the bottom of the frame 10 will be in close contact with the bottom frame member 4 of the window frame, and the intermediate portion of the screen frame 10 to which the angle member 26 is secured will be forced into close con-

tact with that portion of the side members 5 of the window frame to which the bracket 50 is secured.

This drawing of the screen frame 10 into close contact with the window frame by means of the spacing bar 30 is accomplished as follows: With special reference to Figures 7 and 8 it will be observed that the cam notch 31 comprises the short inclined surface 70 disposed nearly at right angles to the longitudinal axis of the spacing bar 30, and the longer inclined surface 71 disposed at but a slight angle to the longitudinal axis of said bar. Further it will be observed that the screw 60 is so disposed in the side member 5 of the window frame that the surfaces of the cam notch 31 will normally at all times contact with said screw.

With special reference to Figure 7 it will be noted that the frame 10 is advancing toward the window frame, as indicated by the arrows, to occupy its closed position. During this movement the spacing bar 30 will ride on the surface of the screw 60 until the cam notch 31 is reached whereupon the bar 30 by its own weight will cause the inclined surface 71 of said notch to be engaged by the screw 60. Continued movement of the parts shown in solid lines in said Figure 7 will cause the screw 60 to occupy the deepest portion of the notch 31 thus bringing the parts into the position shown in dashed lines. Figure 8 shows the screen frame 10 in full closed position and from this figure and Figure 7 it will be seen that during the final step of closing the screen frame 10 the short inclined surface 70 contacts with the screw 60. During the successive steps therefore in closing the screen 10, it will be seen that the screw 60 serves as a fulcrum for the spacing bar 30 as a lever. That is to say, the free end of the bar 30 becomes the operative end of a lever which when turned about the screw 60 as a fulcrum forces the screen frame 10 into close contact with the window frame 1 due to the spacing of the cam notch 31 and the said screw 60. When the frame 10 has contacted with the side members 5 of the window frame as above described, the spacing bar 30 is in a depending position such as shown in Figure 2 and may be then locked in such position as by the bolt 41 of the latch 40. Thus it will be seen that the screw 60 serving as a fulcrum determines the position of the pivot pin 27, as well as the position of the foot 35 of the spacing bar 30 when the screen is closed.

In the modified application, shown in Figure 11, the spacing bar 30, the angle member 26, and the latch 40 have been applied to the cover of a trap, or man-hole, such as are provided in roofs. The bracket member 50 is applied to the box framing of the man-hole as shown and bears the same relative position to the spacing bar 30 and latch 40

as it did in its application to the window and screen above described. That is to say, the cover 100 is hinged as at 101 to the box framing 102 in the roof 103, and the angle member 26 is disposed on the under side of said cover in such a position, relative to the latch 40 also on the under side of said cover, that when the cover is in closed position as shown in solid lines in Figure 11 the foot 35 of said bar 30 may be engaged in locked position by the bolt 41 of the latch, exactly as was the case in Figure 2 of the drawings. If desired to open the cover 100 only partially or to a position as indicated in dashed lines in said Figure 11, the thumb knob 52 on the bracket 50 is engaged in such a hole 32 as will give the desired opening of said cover. In every respect the latch 40, the spacing bar 30 and its associated member 26, and the bracket 50 are the same as the latch, spacing bar, angle member and bracket as disclosed above in relation to a window screen, and therefore the operation of these parts is exactly the same as was the operation above described.

In Figure 12 is illustrated a modified form of bracket corresponding to the bracket 50 above described. In this modification there is provided a casting comprising a base plate 120 adapted to be permanently secured to the frame 121 of any opening as by the screws 122. Rigidly secured at one end of the plate 120 is the lug 123 and likewise at the opposite end is a similar lug 124. Suitably secured in pivotal relation to the lug 123 as by the loose rivet 125 is the bridge or plate 126 of such a length as will extend from the lug 123 to the lug 124 and which may be secured to the lug 124 as by the screw 127 threaded into said lug. Thus the bridge 126 is secured to the base plate 120 in spaced relation thereto sufficient to slidably receive the spacing bar 30. Disposed centrally of the bridge 126 is the thumb screw 130 threaded through said bridge and adapted to engage any one of the holes 32 located in the spacing bar 30. The advantage of the modified form of bracket shown in Figure 12 over the bracket 50 above described is apparent but may be briefly stated as follows. The continued removal and insertion of the screw 60 from the bracket 50 in order to allow the spacing bar 30 to be positioned and removed from the said bracket will in time so destroy the material of the window frame as to make it imperative to either locate the screw 60 in a different portion of the window frame or else move the entire bracket 50 to a different position thereon. The former contingency would be a serious mistake since the screw 60 serves as the fulcrum for the spacing bar 30 in order to secure the closure in tight relation to the opening.

The construction shown in Figure 12 obviates this difficulty, in that the bracket 120

is adapted to be permanently secured to the frame of the opening and only the screw 127 removed in order to permit the placement and displacement of the spacing bar 30. Since the parts 120, 123, 124, 125, 126 and 127 are all constructed of metal, there will be little if any wear on the parts as will be obvious. In this respect of course the lug 124 serves as the fulcrum for the spacing bar 30 and as its position is always fixed relative to the window casing, the continued removal of the spacing bar 30 will never cause to exist an ultimate state of condition as that described above with the use of the bracket 50 and screw 60. With either type of bracket, that is, 50 or 120, it is to be noted that the closure may be retained in an open position by means of the notch 33 in the bar 30, see Figure 10, which will engage with the proper element of the bracket, as clear from Figure 1 of the drawings. That is to say, the notch 33 being at the free extremity of the spacing bar 30 will, when engaged with the screw 60 of the bracket 50, or the lug 124 of the bracket 120, hold the closure in a substantial open position.

It is to be understood that the closure fasteners above disclosed will be utilized in pairs. That is to say, in the use of these fasteners there will be one applied to the left side of said closure and another fastener disposed on the right side of said closure. Stated in still other words, as is well understood, these fasteners will be made in rights and lefts.

It is obvious that those skilled in the art can vary the details of construction as well as the arrangements of parts without departing from the spirit of the invention, therefore it is not desired to be limited to the foregoing except as may be called for by the claims.

What is claimed is:

1. In a device of the character described the combination of a casing surrounding an opening; a closure for said opening, provided with a frame pivoted to said casing; a spacing bar provided with a cam surface pivoted to said frame; a bracket adapted to receive and guide said spacing bar; means to secure said bracket to said casing including a fulcrum around which said bar and cam surface are adapted to turn to tighten said closure; and means for securing said spacing bar in a locked position.
2. In a device of the character described the combination of a casing surrounding an opening; a closure for said opening provided with a frame pivoted to said casing; a spacing bar pivoted to said frame; a fixed bracket secured to said casing and having a fastening ear spaced therefrom to provide a space adapted to receive and guide said spacing bar; a fulcrum associated with said bracket around which said bar is adapted to

65 130

turn to tighten said closure; and means carried by said frame for securing said spacing bar in a locked position.

3. In a device of the character described
5 the combination of a casing surrounding an opening; a closure for said opening provided with a frame pivoted to and adapted to tightly fit said casing at the top thereof; a spacing bar provided with a cam surface
10 pivoted to said frame; a bracket adapted to receive and guide said spacing bar and to

hold the same in adjusted position; securing means for said bracket including a fulcrum around which said bar and cam surface are adapted to turn to tighten said closure at an 15 intermediate point thereof; and means for fastening said spacing bar in locked position while tightly securing said closure at the bottom thereof.

In testimony whereof I affix my signature.

HENRY E. THOMPSON.
